INVENTOR,

Felix Gottschalk.

BY

W. J. Beeman

ATTORNEY.

UNITED STATES PATENT OFFICE.

FELIX GOTTSCHALK, OF NEW YORK, N. Y.

RESISTANCE-CUP.

No. 928,652.

Specification of Letters Patent. Patented July 20, 1909.

Application filed June 3, 1908. Serial No. 436,408.

To all whom it may concern:

Be it known that I, FELIX GOTTSCHALK, a citizen of the United States of America, and resident of New York, in the county of 5 New York and State of New York, have invented certain new and useful Improvements in Resistance-Cups, of which the following is a full, clear, and exact description.

This invention relates to resistance-cups 10 for telephone-transmitters, and more especially to those of microphones in which granular or finely-divided material, such as powdered carbon, is used as the resistance-varying medium, and it has for one of its 15 objects the provision of an instrument of this kind, in which the carbon granules between the electrodes will be prevented from packing into practically a solid body.

My invention has, furthermore, for its 20 object the provision in the carbon-receiving cup, of a series of partitions made of insulating material whereby the granules are separated into small quantities which, however, are in contact with the top and bottom electrodes.

A further object of this invention resides in the combination, with the carbon-cup, of a flexible multi-partitioned device which may be inserted or removed from the cup.

30 Experience has demonstrated the fact that the granulated carbon between the electrodes is apt to become packed under certain atmospheric conditions, in which the temperature constitutes one of the factors to be taken in consideration, so that when any contraction of the metal cup takes place, the resulting compression of the carbon granules will be apt to pack the latter, thus rendering the sound-transmission defective and causing the 35

40 carbon to heat, which latter fact, in turn, causes "frying". By virtue of my present invention I am enabled to avoid the objections sufficiently for all practical purposes, inasmuch as I divide the granular mass into

45 a series of smaller quantities separated from each other by flexible partitions which will compensate for any compression resulting from atmospheric changes and also for the expansion of the carbon caused by heat due

50 to short circuit, and which will adapt themselves to the rapid interchange in position of the granules during the different retractions of the diaphragm. Furthermore, inasmuch as the location of the partitions relative to the electrodes remains permanent, it

is evident that each separate mass of granules

between two adjacent partitions will naturally retain its position, so that a transmitter fitted with my improvement may be held in any position without loss of electrical 60 conductivity. In fact, my improved device constitutes what may be termed a "multiple" electrode, each portion of which forms a separate conductor.

The invention is illustrated in the accompanying drawings, in which similar characters denote similar parts, and in which:—

Figure 1 is a central sectional view of the casing of a telephone transmitter equipped with my improved electrode. Fig. 2 is a 70 front view thereof, the cap and mouth piece being removed; Fig. 3 shows a section of my improved electrode, on an enlarged scale; Fig. 4 is a perspective view of the carbon separator, and Fig. 5 is a front view of a 75 modification of the separator.

In the drawings, T denotes in a general way the transmitter of a telephone, comprising a shell 10, and a casing or cap 11 on which the several elements of the device are 80 supported. Secured to the cap 11 is a bridge 12, carrying a post 13 which holds the bottom electrode 14, fitted into a casing 15 of the resistance-cup but separated therefrom by an annular ring 16 of insulating material. 85 The forward end of the casing 15 is screw-threaded to receive a cap plate 17 which serves to firmly clamp in place a disk of mica 18 whereby the cup casing is thus closed, and which is disposed between the 90 top electrode 19 and a washer 20, these parts being held together by a stud 21 whereby the cup is also attached to the diaphragm 22, which may be held in place in any suitable manner.

95 Disposed within the carbon-cup is a multi-partition member 25 which in its preferred form comprises an annular wall 26 (see Fig. 4) serving as a means for spacing and holding a number of partitions 27 whereby the 100 cup chamber is divided into a series of separate compartments within which granulated carbon is placed so as to entirely fill the cup-chamber. The depth of the member 25 is such as to fill the space between the electrodes 105 14 and 19, so that the several carbon masses in the compartments will be practically independent of each other, and each will constitute a separate and distinct medium for receiving and transmitting the electric current passing from one electrode to the other.

110 In order to produce the desired results

previously mentioned, the member 25 is made of a yielding insulating material which is also capable of withstanding heat such as may be generated by the resistance on the 5 part of the carbon to the electric current.

In Fig. 5 I have illustrated a modification of the partition-member 25, the several divisions of which are separated from each other by circular partitions 28, and cross-partitions 29, it being evident that this formation of the partitions will be as effective as that indicated in Fig. 4.

I claim:—

1. In a resistance cup for telephones or 15 similar instruments, the combination with a casing, a pair of electrodes disposed in said casing and insulated from each other, and granular conducting material between the electrodes, of a member disposed within said 20 casing and made of insulating material and comprising a series of flexible partitions to divide said conducting material into separated quantities.

2. In a resistance cup for telephones or 25 similar instruments, the combination with a casing, a pair of electrodes disposed therein and insulated from each other, and granular conducting material between the electrodes, of a separating member disposed within said 30 casing and comprising a series of flexible partitions extending between and contacting with the electrodes and for dividing the conducting material into separate quantities.

3. In a resistance cup for telephones or

similar instruments, the combination with a 35 casing, a pair of electrodes disposed therein and insulated from each other, and granular conducting material between the electrodes, of a separating member disposed between said electrodes and comprising a series of 40 partitions made of yielding material and for dividing said conducting material into separated quantities.

4. In a resistance cup for telephones or 45 similar instruments, the combination with a casing, a pair of electrodes disposed therein and insulated from each other, and from the casing, and granular conducting material between and contacting with the electrodes, of a separating member interposed between the 50 electrodes and made of heat resisting and yielding material and for dividing said conducting material into separated quantities.

5. The combination with a cup, a pair of electrodes disposed in said cup, granular 55 material disposed between the electrodes and comprising a series of flexible partitions extending between the electrodes and for dividing said conducting material into separate quantities, and a cap for closing said 60 cup and for bringing the opposite edges of said member into contact with the electrodes.

Signed by me at New York, N. Y., in presence of two subscribing witnesses.

FELIX GOTTSCHALK.
